United States Patent Office

Des. 212,322
Patented Oct. 1, 1968

212,322

BOTTLE OR SIMILAR ARTICLE

Victor Koenigsberg, 702 Hall St.,
Franklin Square, N.Y. 11010

Filed Nov. 21, 1967, Ser. No. 9,490

Term of patent 14 years

(Cl. D9—169)

FIG. 1

FIG. 2

FIG. 3

FIG. 4

FIG. 5

FIG. 1 is a front elevational view of a bottle or similar article embodying my new design;

FIG. 2 is an elevational view looking from the right of FIG. 1;

FIG. 3 is a rear elevational view;

FIG. 4 is a top plan view; and

FIG. 5 is a bottom plan view thereof.

I claim:

The ornamental design for a bottle or similar article, as shown.
